TEXTILE SPINDLE

Jacob Harry Gray, Cranston, and Hans H. Wormser, East Greenwich, R. I., assignors to Universal Winding Company, Cranston, R. I., a corporation of Massachusetts

Application March 29, 1952, Serial No. 279,433

7 Claims. (Cl. 74—573)

The present invention relates to textile spindles and more particularly relates to such a spindle capable of rotating an out-of-balance bobbin at high speed.

In the following specification and claims the term "yarn" is employed in a general sense to apply to all kinds of strand material, either textile or otherwise, and the designation "package" is intended to mean the product of a winding machine whatever its form.

In their endeavor to reduce manufacturing costs and to increase output, textile mills are attempting to run their spinning and twisting spindles at very high speeds. For example, speeds of 12,000 to 14,000 R. P. M. are not at all uncommon and attempts are being made to run at even higher speeds. To operate successfully at these high speeds the package of yarn rotated by the spindle must be very well balanced, i. e. its center of gravity should coincide with its geometric axis of rotation. As a practical matter it is impossible to obtain bobbins filled with yarn that are perfectly balanced with the result that when the available out-of-balance bobbins are rotated at high speed an intense vibration is set up by the bobbin as if attempts to rotate about its free axis and is restrained from so doing by the spindle blade. The vibration thus set up is transmitted from the spindle blade to the spindle bearings, spindle step, spindle swing, and to the frame of the over-all machine. Such vibration is extremely noisy and bothersome, but more important, it induces a drag in the spindle causing it to use excessive amounts of power and, if it is permitted to continue, it will destroy the bearings supporting the blade and cause the bearing surfaces on the blade itself to become burned and scored.

Attempts have been made to eliminate or reduce vibration caused by out-of-balance bobbins. One type of such spindle has the spindle blade loosely mounted on the spindle step so that the blade is free to oscillate under the influence of an out-of-balance bobbin, to permit the bobbin to rotate about an axis closer to its free axis. Such an arrangement is not the complete solution to the problem. This type of spindle can handle only a limited amount of out-of-balance and when operating within those limits considerable vibration is set up by the oscillation of the blade, and in addition the rapid oscillation of the step bearing and blade in the spindle step agitates the oil contained therein to such an extent that some of it escapes therefrom with attendant damage to the fibers being twisted, due to oil stain, and destruction of the spindle bearings due to lack of lubrication.

An improved type of spindle for rotating out-of-balance bobbins at high speed is disclosed in application Serial Number 159,345, filed May 1, 1950, by Charles C. Bell for "Textile Spindle." This spindle is provided with a flexible blade adapted to bend or flex under the influence of an out-of-balance bobbin to permit the bobbin to rotate about, or an approximation of, its free axis. This spindle, while capable of handling greater amounts of out-of-balance than the previously described spindle is incapable of rotating severely out-of-balance bobbins at high speed.

Another problem encountered in the prior art spindles involves getting them to pass through their critical speed of vibration without assistance from the operator. Many of the bobbins that could be successfully rotated at high speed by the prior art spindles set up such intense vibration in the spindle when it reaches its critical speed of vibration that the power available to the spindle is not sufficient to accelerate it through that critical speed. If the operator happens to notice that the spindle is not

passing through its critical speed he can often help it through by pressing it firmly against the driving belt to make more power available to it and to dampen out some of the vibration. If the operator fails to notice the spindle's inability to pass through its critical speed, the intense vibration will in time ruin its bearings, and also all of the yarn twisted while the spindle is so operating will be waste because it will not have the desired number of turns of twist inserted therein.

Accordingly it is one object of the present invention to provide a textile spindle capable of continuously rotating a severely out-of-balance bobbin of yarn at high speed.

Another object of the present invention is to provide a textile spindle capable of continuously rotating an out-of-balance bobbin of yarn at high speed and provided with means for counterbalancing all, or a portion of, the out-of-balance present in the bobbin.

Another object of the present invention is to provide a textile spindle capable of continuously rotating a severely out-of-balance bobbin of yarn at high speed and provided with means for counterbalancing a portion of the out-of-balance present in the bobbin and having a portion of the spindle blade adapted to flex to allow said bobbin to rotate around an axis passing through, or adjacent, its resultant free axis.

Another object of the present invention is to provide a textile spindle capable of continuously rotating an out-of-balance bobbin at high speed and provided with vibration damping means to assist said spindle to pass through its critical speed.

Other objects of the invention will in part be obvious and will in part appear hereinafter.

The invention accordingly comprises the apparatus possessing the construction, combination of elements and arrangement of parts which are exemplified in the following detailed disclosure, and the scope of the application of which will be indicated in the claims.

For a fuller understanding of the nature and objects of the invention, reference should be had to the following detailed description taken in connection with the accompanying drawing wherein:

Figure 1 is an elevational view, partly in section of a spindle incorporating the present invention; and

Figure 2 is a view similar to Fig. 1 but illustrating the manner in which the spindle functions to rotate an out-of-balance bobbin at high speed.

The present invention will be described herein as applied to a spindle particularly adapted to use on an "uptwister." It will be understood, however, that it is not intended to limit the invention to an uptwister spindle and that it can be applied to all types of textile spindles, as for example, spindles for use with "ring-twisters," "cap twisters" and "spinning machines."

The present invention provides a spindle for inserting twist in a strand of yarn. The spindle comprises a spindle blade having an upper portion thereof adapted to rotatably carry a package of yarn which comprises the supply of material to be twisted, a lower portion rotatably mounted in a spindle step by means of spaced upper and lower bearings, and a spindle whorl fixedly secured to the blade adjacent the lower end of the upper portion thereof and adapted to be pressed against a driving belt to rotate the spindle blade. The spindle whorl is provided with a plurality of movable counterbalancing weights or washers which are capable of shifting in said whorl under the influence of vibration caused by an out-of-balance bobbin to counterbalance wholly, or in part, the unbalance present in said out-of-balance bobbin. The lower portion of the spindle blade is relatively flexible and comprises a cantilever beam spring which is adapted to flex under the influence of out-of-balance not wholly compensated by the counterbalancing weights or washers to permit the upper blade portion to be displaced laterally to a position which corresponds to, or is a close approximation of, the resultant free axis of the bobbin to permit said bobbin to be rotated about its free axis or said close approximation thereof. The lower or step bearing supporting the spindle blade is loosely mounted for limited movement in the spindle step and is immersed in a bath of oil which damps its movement in response to relatively low frequency vibration and which substantially prevents its

movement in response to high frequency vibration. The vibration damping effect attained by the step bearing reduces or damps the vibration present in the spindle as it passes through its critical speed of vibration to make it possible for the spindle to pass through said critical speed without assistance from the operator.

Referring now to the drawing wherein there is disclosed a preferred embodiment of the present invention comprising a spindle step 10 formed from a hollow upper portion 12 and a hollow lower portion 14. The outer diameter of the lower end of portion 12 is reduced to form an annular shoulder 16 and to permit said lower end to be pressed into the upper end of lower portion 14. Before upper and lower portion 12 and 14 are assembled as above described an annular spindle mounting flange 18 is placed on the lower end of upper portion 12 and against shoulder 16. Mounting flange 18 is held in position on step 10 by reason of being clamped between shoulder 16 and the upper end of lower portion 15. Preferably, a ring of brazing metal is interposed between mounting flange 18 and the upper end of lower portion 14 when step 10 is assembled and the unit is then furnace brazed to form a unitary element. A whorl lock clip 19 is slidably carried by flange 18 in groove 21 formed in its periphery and is adapted to selectively prevent or permit removal of the spindle blade from step 10.

Spindle step 10 is adapted to be resiliently mounted in an opening provided in a spindle swing 20, which may be of any convenient design, by means of spindle step flange 18 and felt washer 22 engaging the upper surface of said spindle swing 20, and spindle mounting spring 24 interposed between the lower surface of spindle swing 20 and mounting nut 26, threaded on lower portion 14 of spindle step 10 all in the manner conventional in the art.

A spindle blade 28, adapted to carry and rotate a package of yarn comprising a bobbin 30 having a supply of yarn Y wound thereon, is rotatably mounted in spindle step 10 by means of upper bearing 32 and step bearing 34. Spindle blade 28 is comprised of an upper substantially rigid portion 36 of sufficient length to pass through the axial opening in bobbin 30 and tapered and appropriate amount to cause said bobbin to firmly seat thereon.

A hollow spindle whorl 38, adapted to engage a driving belt, not shown, to rotate spindle blade 28 in a conventional manner, is rigidly attached to said spindle blade at the lower end of tapered portion 36. The diameter of the bore of whorl 38 is larger than the outside diameter of upper step portion 12 to permit said whorl to telescope over said upper portion when blade 28 is assembled in step 10, and to permit said whorl to cock with said blade without interfering with said step. The lower edge of whorl 38 is provided with a hollow flange 40 which is adapted to be engaged by whorl lock clip 19 to prevent blade 28 from being withdrawn from step 10. A plurality of shiftable counterbalancing washers 42 are carried in the interior of hollow flange 40. Washers 42 are retained in hollow flange 40 by means of a ring closure 44 frictionally retained in the lower edge of whorl 38. Washers 42 are freely movable in flange 40 and are shiftable therein in response to forces set up after blade 28, whorl 38 and bobbin 30 pass through their primary critical speed to counterbalance dynamic out-of-balance present in this rotating system. Washers 42 are preferably formed from a heavy wear resistant material such as iron or steel to obtain as much mass as possible for counterbalancing purposes and surfaces which will not wear excessively. The dimensions of washers 42 are preferably selected to give the maximum counterbalancing effect from the available mass and space. It will be appreciated that a washer that would have the maximum possible movement in hollow flange 40 would necessarily be relatively light due to the need for a large bore to clear spindle step 10 and a small outer diameter to permit maximum movement. Washers of this type would not have the maximum counterbalancing effect due to their light weight. Also the converse is true, the heaviest possible washer will not give maximum counterbalancing inasmuch as the large outside diameter will permit only limited movement. It has been found, for example, that with a flange 40 having an internal diameter of substantially one and one half inches, washers having an outside diameter of substantially one and three eighths inches, and a bore just large enough to clear step 10 when the washers are against the wall of flange 40 and whorl 38 is tipped will give the maximum counterbalancing effect.

A crowned bearing surface 46 is formed on blade 28 adjacent upper portion 36 and a cylindrical bearing surface 48 of smaller diameter than bearing surface 46 is provided adjacent the lower end of blade 28. Bearing surface 46 is crowned to permit it to cock in upper bearing 32 without jamming as step bearing 34 moves in step 10 and as the flexible portion of blade 28 bends. The amount of crown given bearing surface 46 preferably is not great. For example, it has been found that a crown having a radius of substantially five inches produces satisfactory results. The lower end of blade 28 is ground flat in a plane substantially at 90 degrees to the axis of said blade to provide a thrust bearing surface adapted to cooperate with a thrust bearing to be described more in detail hereinafter. The lower end of blade 28, between bearing surface 48 and the flat lower end thereof is preferably tapered as at 50 at approximately a 45 degree angle to facilitate inserting bearing surface 48 into step bearing 34 and to reduce the area of said flat thrust surface.

10 The diameter of blade 28 is preferably considerably reduced immediately below bearing surface 46 by means of a smoothly curved shoulder 47 so that the length 52 of blade 28 which is located between bearing surface 48 and shoulder 47 is relatively flexible.

15 20 The bore of upper portion 12 of spindle step 10 is enlarged at the top thereof to provide a bearing receiving recess 54 above annular internal shoulder 56. A self-lubricating anti-friction bearing 58 is located in bearing recess 54 to cooperate with crowned bearing surface 46.

25 30 Anti-friction bearing 58 is preferably a roller bearing comprising a plurality of relatively short rollers 60 to permit crowned bearing surface 46 to cock as the relatively flexible length 52 of blade 28 flexes under the influence of an out-of-balance package of yarn without causing the bearing to jam or lock. Rollers 60 are supported vertically by washer 62 which rests on shoulder 56. An outer bearing race 64 is supported against lateral movement by the wall of bearing recess 54 and vertically by washer 62. Rollers 60 are spaced circumferentially

35 40 around race 64, and prevented from falling out of position when blade 28 is removed from step 10 by a cage or roller retainer (not shown) of any convenient design. Rollers 60 and race 64 are held in bearing recess 54 by bearing retaining and lubricating ring 66, preferably formed of an oil impregnated sintered bronze material, but which can be formed from any other convenient porous material which possesses a sufficient degree of hardness and which is non-abrasive, locked in bearing recess 54 by washer 68 which engages the top of said ring 66. The upper edge of upper step portion 12 is rolled inwardly over the outer edge of washer 68 to lock it and the entire upper bearing assembly 32 in step 10. The bore of bearing retaining and lubricating ring 66 flares outwardly at its lower end to a diameter slightly smaller than the inner diameter of bearing race 64 so that it extends over and is adapted to contact the small area of the end of each roller 60 to prevent their vertical displacement and transmit thereto a small quantity of oil. The upper end of bearing retaining and lubricating ring 66 is provided with a rabbet 70 which cooperates with the inner wall of bearing receiving recess 54 to form a groove which is packed with an oil impregnated felt ring 72. Washer 68 is provided with an oil hole 74 located above felt ring 72 through which oil can be applied to said felt ring to replenish the oil carried thereby as it is used in the normal operation of the spindle.

45 55 60 Step bearing 34 comprises a plug member 76 which closes the lower end of lower portion 14 of spindle step 10 and is held in place therein by any convenient means. The upper surface of plug 76 is provided with a transverse slot 78 which receives a tongue member 80 formed on the bottom of a cup-shaped journal holding member 82. A bushing 84, preferably formed of an oil impregnated sintered bronze material but which can be formed of any other convenient bearing material, is located in and tightly held by cup-shaped member 82. Bushing 84 is adapted to cooperate with bearing surface 48 on spindle blade 28 to journal the lower end of said blade. The upper end of bushing 84 is provided with

65 70 75 80 85 a flange 86 having a diameter slightly smaller than the bore of lower step portion 14. The diameter of cup-shaped journal holding member 82 is also smaller than the bore of lower step portion 14 and is substantially equal in diameter to flange 86. Tongue member 80 is narrower than transverse slot 78 by an amount substantially equal

to the difference between the diameter of cup-shaped member 82 and the bore of lower step portion 14. It will, therefore, be seen that step bearing assembly 34 is free to oscillate in spindle step 10 while it is held against rotation. The space between step bearing assembly 34 and the wall of lower step portion 14 is filled with oil to damp the oscillation of said step bearing assembly under the influence of an out-of-balance bobbin. Preferably the space between step bearing assembly 34 and spindle step 10 is relatively small, in the order of from .005 inch to .015 inch, and the oil contained in said space is of such a viscosity that said step bearing assembly 34 is held against substantially any movement when it is subjected to vibrations ranging from 3,000 cycles per minute upwardly, and damps the movement of said step bearing assembly under the influence of vibrations below 3,000 cycles per minute.

The lower end of bushing 84 is enlarged to form an axial pocket 88. A thrust ball 90 is loosely contained in axial pocket 88 and rests on a hardened plate 92 interposed between the lower end of bushing 84 and the bottom of cup-shaped member 82. It will thus be seen that the spindle blade 28 is rotatably mounted in spindle step 10 by means of upper bearing 32 and lower bearing 34 and that thrust ball 90 provides a thrust bearing for the end of blade 28 to support the weight of said blade and the weight of the package of yarn carried thereby. The fact that thrust ball 90 is loosely contained in axial pocket 88 permits it to roll around a circular part bounded by the wall of said pocket to cause said ball to be in rolling contact with the flat thrust surface on blade 28 thus providing an anti-friction thrust bearing for said blade.

When a dynamically out-of-balance object is rotated at high speed there is a strong tendency in that object to rotate about its free axis. When such an out-of-balance object is prevented from rotating about its free axis, as by a rigid shaft or by a rigid spindle when the out-of-balance object is a textile package, its attempts to rotate about its free axis sets up vibration in the shaft or spindle, the intensity of which is a function of the degree of out-of-balance. When an out-of-balance textile package is rotated by the spindle of the present invention the shiftable counterbalancing washers 42 move in hollow flange 40 of spindle whorl 38 to counterbalance wholly or in part the out-of-balance of the bobbin in a manner to be described more fully hereinafter. In the event counterbalancing washers 42 are not capable of completely counterbalancing the out-of-balance present in the bobbin the remaining or resultant amount of out-of-balance causes the package to attempt to rotate about its free axis and causes the flexible portion 52 of blade 28, located between its bearing surfaces 46 and 48, to bow or flex. This bowing or flexing of blade portion 52 permits blade 28 to fulcrum around upper bearing 32, as illustrated diagrammatically in Fig. 2, to displace its upper rigid portion 36 laterally from the axis of bearings 32 and 34 to allow the textile package to rotate around its free axis or a close approximation thereof, thus eliminating, or reducing to acceptable limits, the vibration due to dynamic out-of-balance. Flexible portion 52 of blade 28 should be flexible enough to permit the out-of-balance package of yarn carried by the spindle to bow or flex a sufficient amount to permit said package to rotate around its free axis or an approximation thereof. At the same time the flexible portion 52 should be sufficiently rigid to resist whip in the spindle, as it passes through critical speeds in starting and stopping.

The lower portion of blade 28, i. e. that portion of the blade extending from the midpoint of that portion of crowned bearing surface 46 adapted to be located between rollers 60 to the midpoint of lower bearing surface 48, forms a cantilever beam spring which fulcrums around anti-friction bearing 58. Preferably the lower portion of blade 28 has a "spring constant" ranging from 100 to 175 pounds per inch of deflection. The term "spring constant" as used in the present specification and claims is defined as the result obtained by dividing a load applied to the free end of a cantilever beam spring by the distance said load deflects said cantilever beam spring, and be expressed by the formula:

$$\text{Spring constant} = \frac{\text{Load}}{\text{Deflection}}$$

The spring constant of the lower portion of spindle blades 85

embodimenting the present invention is measured by clamping the blade rigidly at the midpoint of that portion of crowned bearing surface 46 adapted to be located between rollers 60 and applying a load at the midpoint of lower bearing surface 48. A spindle blade having a lower portion having a spring constant included in the range of from 100 to 175 pounds per inch of deflection determined in the above described manner is sufficiently rigid to resist the above described whip, when the spindle is rotating typical spindle bobbins in commercial use today at 16,000 R. P. M., and is flexible enough to permit any commercially produced yarn package normally employed on twisting machines to rotate about its free axis, or a close approximation thereof. However, a spindle blade having a lower portion wherein the spring constant when measured as above described, is as low as 50 pounds per inch of deflection will function satisfactorily with many bobbins, and a spindle blade having a flexible portion wherein the spring constant is as high as 300 pounds per inch of deflection gives an appreciable reduction in vibration as compared with all prior art spindle blades, and a spring constant higher than 175 pounds per inch of deflection but not exceeding 300 pounds per inch of deflection is of advantage in some applications.

The flexible length of blade 52 in addition to permitting an out-of-balance bobbin to rotate about its free axis, or an approximation thereof, also lowers the critical speed of the rotating system, when it is carrying a load such as a bobbin of yarn or an empty bobbin, considerably below that of a conventional rigid spindle. This critical speed, therefore, is well below the normal operating speed of the spindle and accordingly little power is required to bring the spindle past it.

In addition to the flexible portion 52 making it easier for the spindle to pass through its critical speed by lowering that critical speed the vibration damping action of step bearing assembly 34 also assists the spindle to pass through its critical speed. As above explained, step bearing assembly 34 is so proportioned that it dampens out relatively low frequency vibrations. Inasmuch as flexible portion 52 lowers the critical speed of the rotating system to within the range of vibrations damped by said step bearing assembly it assists the spindle to pass through its critical speed by subduing the attendant vibrations.

In addition to the vibrations set up by unbalance in the package of yarn being rotated, spindles are subjected to many other vibrations and shocks. The great majority of these other vibrations are of relatively low frequency and are caused by such things, for example, as the impact of the spindle driving belt joint with the spindle whorl, out-of-balance components in other parts of the machine, disturbances in adjacent machines, etc. The vibration damping step bearing assembly 34 functions to dampen out all of these other vibrations and prevent them from either passing from the spindle to the machine or passing from the machine to the spindle.

The spindle of the present invention functions in the following manner when rotating an out-of-balance bobbin of yarn. As the spindle accelerates, the out-of-balance bobbin causes vibration to take place. Upon the spindle passing through its primary critical speed, which as stated above is comparatively low, the shiftable counterbalancing washers 42 move in hollow whorl flange 40 to a position wherein they tend to counterbalance the out-of-balance present in the bobbin. It will, of course, be understood that in many instances the amount or degree of out-of-balance present in the bobbin may be so great that washers 42 cannot completely counterbalance it in which case they function to reduce the amount of out-of-balance present in the rotating system. If the mass of washers 42 is sufficient to completely counterbalance the bobbin of yarn the spindle passes through its critical speed and rotates about its axis completely free of any vibration. If washers 42 do not have enough mass to counterbalance the bobbin of yarn after the spindle passes through its critical speed the resultant or remaining out-of-balance in the rotating system causes the flexible length 52 of blade 28 to flex or bend in the manner illustrated in Fig. 2 to permit said bobbin to rotate about its free axis or an approximation thereof in the above described manner. As the spindle passes through its critical speed an intense but relatively low frequency vibration is set up which tends to oscillate blade 28 and step bearing 34. This oscillation is permitted but is

damped, to assist the blade in passing through its critical speed, by means of the oil contained in the space between step bearing assembly 34 and the wall of spindle step 10. After the spindle has passed through its critical speed and has attained its normal high operating speed a certain amount of vibration will be present if the amount of out-of-balance in the bobbin of yarn is so great that washers 42 cannot completely counterbalance it and flexible length 52 cannot flex sufficiently to permit it to rotate about its free axis. When the spindle of the present invention is operating under the last described conditions step bearing 34 is held substantially motionless by the oil surrounding it inasmuch as the area of the space surrounding said step bearing is so small that there is not time for the damping oil to move from one side of step 10 to the other under the influence of the high frequency vibrations.

Since certain changes may be made in the above apparatus without departing from the scope of the invention herein involved, it is intended that all matter contained in the above description or shown in the accompanying drawing shall be interpreted as illustrative and not in a limited sense.

What is claimed is:

1. A textile spindle adapted to rotate a package of yarn at high speed comprising a spindle blade, a spindle step, a plurality of bearings in said step supporting said blade for rotation, a hollow whorl mounted on said blade, and a movable weight located in said whorl and adapted to shift to counterbalance an out-of-balance package of yarn rotated by said blade.

2. A textile spindle adapted to rotate a package of yarn at high speed comprising a spindle blade, a spindle step, a plurality of bearings in said step supporting said blade for rotation, a hollow whorl mounted on said blade, and a plurality of movable washers located in said whorl and adapted to shift to counterbalance an out-of-balance package of yarn rotated by said blade.

3. A textile spindle adapted to rotate a package of yarn at high speed comprising a spindle blade, a spindle step, a plurality of bearings in said step supporting said blade for rotation, a whorl mounted on said blade, a hollow flange on said whorl, and a plurality of movable washers located in said hollow flange and adapted to shift to counterbalance an out-of-balance package of yarn rotated by said spindle.

4. A textile spindle adapted to rotate a package of yarn at high speed comprising a spindle blade, a whorl mounted on said blade, a spindle step, spaced bearings in said step supporting said blade for rotation, and a movable weight carried by said whorl, said blade, whorl, movable weight and a package of yarn carried by said blade comprising a rotating system, the portion of said blade located between said bearings being flexible to reduce the critical speed of said rotating system, said movable weight being adapted to shift after said rotating system passes through its critical speed to counterbalance any out-of-balance present in the package of yarn rotated by said blade, said flexible portion also being adapted to flex under the influence of any unbalance not fully counterbalanced by said weight.

5. A textile spindle adapted to rotate a package of yarn at high speed comprising a spindle blade, a spindle step, spaced bearings in said step supporting said blade for rotation, a hollow whorl mounted on said blade, and a movable weight located in said whorl, said blade, whorl, movable weight and a package of yarn carried by said blade comprising a rotating system, the portion of said blade located between said bearings being flexible to reduce the critical speed of said rotating system, said movable weight being adapted to shift after said rotating system passes through its critical speed to counterbalance any out-of-balance present in the package of yarn rotated by said blade, said flexible portion also being adapted to flex under the influence of any unbalance not fully counterbalanced by said weight.

6. A textile spindle adapted to rotate a package of yarn at high speed comprising a spindle blade, a spindle step, spaced bearings in said step supporting said blade for rotation, a hollow whorl mounted on said blade, and a plurality of movable washers located in said whorl, said blade, whorl, movable washers and a package of yarn carried by said blade comprising a rotating system, the portion of said blade located between said bearings being flexible to reduce the critical speed of said rotating system, said movable washers being adapted to shift after said rotating system passes through its critical speed to counterbalance any out-of-balance present in the package of yarn rotated by said blade, said flexible portion also being adapted to flex under the influence of any unbalance not fully counterbalanced by said washers.

7. A textile spindle adapted to rotate a package of yarn at high speed comprising a spindle blade, a spindle step, spaced bearings in said step supporting said blade for rotation, a whorl mounted on said blade, a hollow flange on said whorl, and a plurality of movable washers located in said hollow flange, said blade, whorl, movable washers and a package of yarn carried by said blade comprising a rotating system, the portion of said blade located between said bearings being flexible to reduce the critical speed of said rotating system, said movable washers being adapted to shift after said rotating system passes through its critical speed to counterbalance any out-of-balance present in the package of yarn rotated by said blade, said flexible portion also being adapted to flex under the influence of any unbalance not fully counterbalanced by said washers.
